UNITED STATES PATENT OFFICE

FREDERICK S. TEW, OF CHEVY CHASE, MARYLAND

DESIGN FOR A BADGE

Application filed March 26, 1931. Serial No. 39,258. Term of patent 3½ years.

To all whom it may concern:

Be it known that I, FREDERICK S. Tew, a citizen of the United States, residing at Chevy Chase, in the county of Montgomery, and State of Maryland, have invented a new, original, and ornamental Design for Badge, of which the following is a specification, reference being had to the accompanying drawings, forming part thereof.

I claim:

The ornamental design for a badge, as shown.

FREDERICK S. TEW.
